UNITED STATES PATENT OFFICE.

RICHARD PREISS, OF CHICAGO, ILLINOIS.

CLOSURE.

Application filed January 13, 1922. Serial No. 528,906.

To all whom it may concern:

Be it known that I, RICHARD PREISS, a citizen of the United States, residing at Chicago, county of Cook, and State of Illinois, have invented a new and useful Improvement in Closures, of which the following is a specification.

This invention relates to closures and more particularly pertains to an improved closure especially adapted for use on the inlets of radiators of motor vehicles and which cannot be lost or easily entirely removed by unauthorized persons.

Among the more important objects and advantages of this invention are: the generally loss-proof and theft-proof construction of the closure or cap whereby its loss or unauthorized removal entirely from the radiator or other device to which it is applied is prevented, yet permitting the manipulation of the cap into open or closed positions; the embodiment of means for firmly locking the cap in closed position; the provision of a cap of the character referred to which is ornamental as well as useful; the embodiment of the features above pointed out and those which may be pointed out or appear later in a compact and simple unit structure which may be applied to any standard make of radiator; and the generally improved structure affording a device of great durability yet simple and capable of being manufactured at low cost.

While this invention is particularly adapted for use as a radiator cap or closure, and for the purpose of convenience is illustrated as such, it will be understood that it finds a wide field of utility for other purposes.

One embodiment of this invention whereby I attain the foregoing and other objects and advantages to be pointed out or appear later is illustrated in the accompanying drawing, in which:

Fig. 1 is an elevational view of a device embodying the improvements of this invention.

Fig. 2 is a bottom plan.

Fig. 3 is a vertical transverse sectional view taken on line 3—3 of Fig. 2, looking in the direction indicated by the arrows.

Fig. 4 is a similar view taken on line 4—4 of Fig. 2, looking in the direction indicated by the arrows.

Fig. 5 is a view similar to Fig. 4, showing the cap in open position.

Referring more particularly to the em-

bodiment of this invention illustrated in the accompanying drawing, the device generally comprises a base portion 5, and the hollow cap or closure 6 disposed thereon. The base 5 is provided with an externally threaded shank 7, which is receivable into the internally threaded upstanding flange 8, which borders the inlet opening 9 in a standard radiator, but a part, 10, of which is shown here. The shank is prevented against rotation in the flange by a pair of radially disposed key-screws 11—11 in the shank and provided with ends 12—12 which impinge upon the flange 8 and lock the base 5 on the radiator. The inner ends of the screws 11 are provided with polygonal sockets 13—13, for reception of a suitable tool for driving the screws home, a pair of case-hardened rods, 14—14, extending vertically in the shank 7, back of the inner ends of the screws to prevent their accidental displacement. The base 5 is formed with an annular shoulder 15, which abuts the upper end of the flange 8.

The base 5 is provided with a central elliptical opening 16 to permit filling of the radiator and the cap 6 is provided for closing this opening. The upper surface of the base 5 is provided with an annular depression 17, which affords a seat for the cap 6, the latter having a complementally formed bottom face 18 adapted to engage the seat. The cap is retained against complete removal from the base 5 by a pin in the nature of a screw 19, forming a permanent pivot element, which enters at the bottom of the cap and passes through a suitable opening 20 in the base 5, the opening being in the nature of an arcuate slot, best shown in Fig. 2, and the head 21 of screw 19 engages beneath the slot 20, an arcuate recess 22 being substantially coextensive with the slot and affording a space for the head 21 of the screw. One end of the slot is enlarged and countersunk as at 23 for receiving the head of the screw when the cap is in open position, as shown in Fig. 5. It will be observed that the slot 20 extends through but a quarter of the circumference of the cap.

Another arcuate slot 25 is provided, and its medial portion is substantially diametrically opposite that of the slot 20, this slot 25 having an enlarged opening 26 at one end, substantially diametrically opposite the countersunk portion 23 of the slot 20. A screw pin 27, functioning as a locking element, projects from the lower face of the

cap 6 at a point diametrically opposite the screw 19, and the said screw 27 is adapted to pass through the slot 25, the latter having an enlarged arcuate recess 28, coextensive therewith for accommodating the head 29 of said screw 27. The opening 26 is of sufficient size to permit of withdrawal of the head of the screw 27 therethrough, when the cap is in open position. The face of the recess 28 is provided with raised portions 30—30, which are located substantially at the medial portion of the recess 28, so that the head 29 of the screw 27 will ride thereunder when the cap 6 is turned on the base 5, as best shown in Fig. 1. The cap 6 is provided with opposite laterally extending arms 31—31 for imparting rotation to the cap, and the upper end of the cap is provided with an opening 32 for connection of a motometer or some ornamental device, not shown.

In operation, when in closed position, the cap 6 is arranged as best shown in Figs. 1, 3 and 4. When it is desired to open the inlet to the radiator, the cap is rotated on the base 5 in a clockwise direction, as viewed in Fig. 2, the screws 19 and 27 traveling in their respective slots until they abut the ends of the slots and are in engagement with the enlarged portions 23 and 26, respectively. The cap can then be raised permitting the screw 27 to entirely clear its respective opening, whereupon the cap is swung to one side as indicated in Fig. 5. The steps outlined above are reversed when closing and locking the cap, the locking function being performed by the head of the screw 27 riding over the raised portions 30—30. These portions 30—30 will prevent any ordinary vibration from rotating the cap while in closed position, thus serving to firmly retain the closure in the desired position, the arms 31—31 lying parallel to the top of the radiator.

While I have described my invention as embodied in a specific structural arrangement, it is obvious that minor changes in the details thereof may be made within the purview of the invention and scope of the claims.

I claim:

1. In a device of the class described, in combination, a base having an inlet opening therein, a closure seating over said opening, and means for guiding said closure in an axial rotative movement relative to said opening, a part of said means forming a pivot for eccentric displacement of said closure relative to said opening.
2. In a device of the class described, in combination, a base having an opening therein, a closure, a pivot member on the closure permanently engaging said base and adapted for concentric movement about the axis of said opening, and a locking member on

said base adapted for concentric movement about the axis of the opening and readily disengageable from the base.

3. In a device of the class described, in combination, a base having an opening therein, a closure, a pair of pin devices on the closure, one having permanent pivotal engagement with the base, and the other adapted for detachable locking engagement therewith, both of said pin devices being adapted for arcuate sliding engagement with the base.

4. In a device of the class described, in combination, a base having an opening therein, a closure, a pair of pin devices on the closure, one having permanent pivotal engagement with the base to permit said closure to be rotated eccentrically to said opening, the other pin device adapted for detachable locking engagement with the base, and both of said pin devices arcuately slidably engaging the base for permitting axial rotation of the closure on said base.

5. The combination with an internally threaded flange, of a base having threaded engagement with the flange and provided with an inlet opening, screws in said base engaging said flange, means within the base for preventing displacement of said screws, and a closure on said base adapted for movement both concentrically and eccentrically relative the opening in said base.

6. In a device of the character described, in combination, a base having an inlet opening therein, a closure for said opening, and a pivot element for connecting said closure to said base, said pivot member being movable through an arc described about the axis of said opening, and being adapted to release the closure when in one terminal position and to lock the closure when in the other terminal position of the arc.

7. In a device of the character described, in combination, a base having an inlet opening therein, a closure for said opening, a pivot element for permanently connecting the closure to the base, said pivot element being movable relative said base on an arc described about the axis of the opening, and a locking element on the closure for detachable engagement with the base and also movable in an arc described about the axis of said opening.

8. In a device of the character described, in combination, a base having an inlet opening therein, a closure for said opening, a pivot element for permanently connecting the closure to the base, said pivot element being movable relative said base on an arc described about the axis of the opening, a locking element on the closure for detachable engagement with the base and also movable in an arc described about the axis of said opening, and means on the base adapted to be engaged by said locking element to

prevent accidental displacement of the cap.

9. In a device of the class described, in combination, a base having a central opening and a seat bordering said opening, a closure receivable upon said seat, said base having a pair of arcuate slots described about the axis of said opening, a pair of pin elements on the closure for engagement in said slots, one of the slots having an enlarged portion permitting disconnection of the pin engaged therewith, and said closure being rotatable on the other pin and permanently connected to the base thereby.

10. In a device of the class described, in combination, a base having a central opening and a seat bordering said opening, a closure receivable upon said seat, said base having a pair of arcuate slots described about the axis of said opening, a pair of pin elements on the closure for engagement in said slots, one of the slots having an enlarged portion permitting disconnection of the pin engaged therewith, and the other

pin having permanent engagement with the base, and one of the slots being distorted to frictionally engage one of said pins.

11. In a device of the class described, in combination, a base, a closure and means for rotatably guiding the closure on said base, said means being axially movable of the base, when in a predetermined position, in which the closure is released from the base.

12. In a device of the class described, in combination, a base, a closure, means for turning said closure about the axis of the base without moving said closure axially of the base, and means for limiting the rotary movement, said limiting means being axially movable of the base.

In testimony whereof, I affix my signature in the presence of two witnesses at W. Randolph St., Chicago, Illinois.
